Assignees to

James G. Abbott and Archibald Lawrence of
Philadelphia, Pa.

Letters Patent #10702 Dated May 1, 1835

The Schedule referred to in their Letters Patent and
making part of the same

I act where it may concern

Be it known that we ~~Garrison~~
Smith, Henry Brown & Joseph A Read of City and County
of Philadelphia and State of Pennsylvania, have produced a
new and original design for

Water Coolers. And we do hereby
declare that the following is a full and clear description of
the same; reference being had to the annexed drawing forming
part of this specification, in which,

Figure 1. is a side view of top piece and rim

Figure 2. is a side view of vase rim, and

Figure 3. is a top view of top piece and rim

Similar characters of reference in the several
figures denote the same part of cooler and design.

The ornamental castings of this cooler consist

Dec. 70 2

of the basin *B.* top rim *R.* and top piece *P.* The first has the downward spread formed by the two curved surfaces *a* and *b*; the lower surface *a.* being embellished with figures *e* and *f* arranged alternately, which figures bear the gothic ornament *d.* in bas-relief. Upon the surface *b.* are the curved ornaments *g* alternating with the figures *h.* which arise from the slight shelf between the two surfaces *a.* and *b.* on which are also the spherical projections *i.* the configuration and arrangement of the whole being shown as fully in the drawings.

The top rim *R.* has a corrugated edge *K.* having alternately long and short terminations *m.* and *n.* in bas-relief, upon curved surface *l.* of the rim, the details being as seen in the drawings.

The top piece *P.* has a flat edge *p* which rests upon the rim *R* and bears the inscription "Abbott & Lawrence, Philad^a Patented 1855" in raised capitals and numerals. From this rim the top rises in a curved dome-like form as shown in the drawing, surmounted by a spreading plume-like ornament *q.* The surface of top piece is embellished in bas-relief by the interlacing of figures *r.* and *s.* and the scale .... like figures *t.* and *u.* the entire design configuration and arrangement being as set forth in the drawing.

What we claim as our invention or production and desire to secure by Letters Patent is,

The design, configuration and arrangement of the herein described Castings and the ornaments in bas-relief thereon, constituting a new and original design for Water Coolers.
